ELECTRICAL SWITCH

Joseph S. Thompson, San Francisco, Calif., assignor to Pacific Electric Manufacturing Corporation, San Francisco, Calif., a corporation of California

Application March 13, 1934, Serial No. 715,263

4 Claims. (Cl. 200—48)

This invention relates generally to the construction of electrical switches for use in conjunction with electrical power distribution systems.

It is an object of the invention to provide a switch of the above character, which will be well adapted for operation by an electric motor or like device without danger of improper closing or breakage of parts resulting from variations in the degree of movement of the operating member. In this connection, my switch is characterized by a relatively wide permissible angle of overthrow of the operating member from that position corresponding to complete initial closing of the switch.

Another object of the invention is to provide an improved arrangement for counterbalancing the switch blade, whereby there will be no undue speeding-up of the operating motor in opening the switch, when the blade is arranged to swing downwardly.

A further object of the invention is to provide a construction and a co-ordination of parts whereby breakage of certain elements will not cause the switch blade to drop open.

Another object of the invention is to provide an improved means for applying pressure to the electrical contacting areas of the switch.

Further objects of the invention will appear from the following description in which the preferred embodiment of the invention has been set forth in detail in conjunction with the accompanying drawings. The appended claims are to be afforded a range of equivalents consistent with the state of the prior art.

Referring to the drawings:

Fig. 1 is a side elevational view illustrating a switch incorporating the present invention.

Fig. 2 is a bottom plan view of the switch shown in Fig. 1.

Fig. 3 is a cross-sectional detail showing the preferred construction of the switch blade and its co-operating contact.

Fig. 4 is a view similar to Fig. 1, but showing the parts of the switch in a different operating position.

Fig. 5 is a cross-sectional detail taken along the line 5—5 of Fig. 1.

Referring first to Fig. 1 of the drawings, the operating parts of my switch are shown carried by a plurality of insulators 10, 11 and 12, which in turn are secured to a structure support member 13. The blade 14 of the switch is carried by leverage mechanism 15 which in turn is secured to the lower end of insulator 11. One

end of blade 14 co-operates with a relatively stationary contact 16, which in turn is carried by the lower end of insulator 10. As representative of suitable means for applying motion to the leverage mechanism 15 to effect opening and closing movements of the switch blade 14, insulator 12 is journaled with respect to the structure support 13, whereby it can be rotated axially by a suitable electric motor or like device. A shaft 18 is coupled to the lower end of insulator 12, and secured to this shaft there is an operating member or lever 19. As will be presently explained, this lever 19 is suitably connected to the leverage mechanism 15 to effect operation of the switch.

A desirable form of contact 16 is illustrated more clearly in Figs. 2 and 3. It is formed of suitable metal, such as brass or bronze, having a pivotal connection 21 with a bracket 22, this bracket being in turn mounted upon the lower end of insulator 10. The outer edge or face 23 of the contact is of sufficient width to afford an adequate electrical contacting area, and is formed on a contour such as shown in Fig. 3 to afford a tapered lower end portion 24. The contact is urged or biased in a clockwise direction about the pivotal connection 21, by means of a compression spring 26. A lug 27 engaging a fixed shoulder 28, serves to limit movement in such direction. An electrical conductor 29 is connected to the contact 16, and, in conjunction with the terminal member 31, facilitates making electrical connections with the circuit in which the switch is to be incorporated.

A desirable construction for the switch blade 14 is shown in Fig. 3, and is as follows:—The blade for the major portion of its length consists of a rigid metal tube 32. Secured to one end of tube 32 there is a contact member 33, which is adapted to co-operate with the relatively stationary contact 13. As illustrated, contact 33 is in the form of a yoke made of suitable metal, such as brass or bronze, having a collar 34 for attachment to the tube 32. The inner face 36 of this yoke is relatively wide compared with the width of contact 16, and is of ample area to afford good electrical contact with the edge face 23 of the contact 16.

In its preferred construction, the switch blade is also provided with a pressure contact to make possible tight clamping engagement with the contact 16 when the switch is closed. Thus, in the construction illustrated, a pair of aligned rods 37 and 38 are slidably disposed within the tube 32. One end of rod 37 carries a pressure

contact 39, which in this instance is semi-cylindrical in form. A spring-biased lost motion connection is interposed between the inner ends of rods 37 and 38, which in the detail illustrated consists of a sleeve 41 in conjunction with a compression spring 42. Sleeve 41 is slidably disposed upon rod 38 and has one end fixed to the adjacent end of rod 37. Compression spring 42 has its one end seated upon a shoulder 43 formed on sleeve 41, and its other end seated upon a collar 44 which is secured to rod 38. The spring therefore serves to urge rods 37 and 38 apart, and such movement is limited by collar 46 mounted upon rod 38. Rod 38 is also urged in one direction by a compression spring 47. Thus, in the detail shown, spring 47 is disposed within a sleeve 48, which in turn is fixed to the tube 32. One end of the spring is seated upon a stationary abutment 49, while the other end is seated upon a collar 51 secured to rod 38.

That end of rod 38 which projects from the end of tube 32 is adapted to be actuated by a cam, as will presently be explained, and it is therefore shown carrying a cam roller 52. Movement of the rod 38, under the urge of spring 47, is limited by engagement of collar 51 with the end tube closure 53.

With the switch blade assembly described above, it is evident that when rod 38 is forced inwardly with respect to tube 32, such movement is initially accompanied by movement of rod 37, until the pressure contact 39 engages the relatively stationary contact 16. Thereafter, movement of rod 37 and pressure contact 39 is arrested, and further movement of rod 37 is taken up by the lost motion connection formed by sleeve 41. Contact 39 is therefore pressed upon the stationary contact 16, in accordance with the compression of spring 42. Such pressure not only serves to establish good electrical connection between pressure contact 39 and the adjacent surface of contact 16, but also serves to tightly press together and make good electrical contact between the faces 23 and 36. In Fig. 3, rod 38 has been shown forced inwardly to such an extent as to secure the desired pressure engagement. While the spring-biased lost motion connection formed by sleeve 41 and spring 42 is deemed desirable, it is not essential, since other means may be provided to afford proper retention pressure upon contact 39.

The leverage mechanism 15 can best be explained by reference to Figs. 1 and 2. In the detail construction illustrated, one end of the tube 32 is gripped by a clamp 55, which in turn carries a pair of spaced arms 57. Arms 57 are provided with a pivotal connection 58 with an L-crank 59. The arms 61 of this crank are provided with pivotal connections 62 to a bracket 63, this bracket in turn being secured to the lower end of insulator 12. The arm 64 of crank 59 is connected to a link 66 which in turn is connected to the crank 19. Thus, when crank 19 is turned, as by rotating insulator 12, crank 59 is swung about the axis of pivotal connection 62, to swing the axis of pivotal connection 58 about an arc of a circle.

In addition to the leverage mechanism just described, means is provided for determining or controlling the motion applied to blade 14 in response to rotation of crank 19, and particularly to provide for continued movement

of the crank 19 after the free end of the blade has been elevated to closed position. Thus, in the construction illustrated (Fig. 2) a cam roller 67 is journaled to the extremities of arms 57. This roller engages within cam slots 68 formed in the parallel depending cam plates 69. The cam plates are stationary, as for example by mounting them upon the bracket 63. A desirable contour for the cam slots is illustrated in Fig. 1. Thus, in this instance each slot includes a nearly upright and linear portion 68a, and a generally arcuate portion 68b. Under certain conditions of counterbalancing, simple cam surfaces may suffice in place of slots, such as would be afforded by omitting the outer loops of slots 68. 15

In order to counterbalance the blade 14 and other moving parts of the switch, I provide a pair of spring counter-balancing units 71 which are pivotally carried by the bracket 72 in which shaft 18 is journaled. The plunger rods 73 of 20 these slots are pivotally connected to the extremities of arms 57. The counterbalancing forces are thus applied in such a manner as to tend to rotate arms 57 in a clockwise direction, as viewed in Fig. 1. It is evident that a single 25 spring counterbalancing unit of proper design will suffice in place of the duplicate units shown.

In order to steady the lower end of rotatable insulator 12, brackets 63 and 72 are connected together by tie rods 74. If desired, these rods 30 can also be incorporated as conductors for the electrical circuit. Thus, as illustrated in Fig. 1, the blade is electrically connected to the tie rods by means of flexible conductors 76. Electrical connection to the tie rods 74 can be made by 35 the terminal member 77.

Reference has previously been made to the fact that the pressure contact 39 is preferably actuated by cam means. Referring particularly to Fig. 1, a secondary cam 81 is shown carried 40 by bracket 63, intermediate the spaced cam plates 69. When the switch is in the closed position shown in Fig. 1, the surface of this cam is engaged by roller 52, and the roller occupies a position with respect to the blade such that 45 pressure contact 39 is being forced into tight engagement with the relatively stationary contact 16.

Operation of my switch is as follows:—An optimum closed position for the switch blade is 50 illustrated in Fig. 1. If it is desired to open the switch, an electric motor or like device serving to rotate insulator 12, is energized. Rotation of crank 19 causes crank 59 to be rotated in a counter-clockwise direction, as shown in this 55 figure, thus causing the cam roller 67 to move downwardly within the portions 68a of the cam slots 68. As long as the cam roller is within the slot portions 68a, the angles assumed by arms 57 in their downward movement serve to retain 60 the free end of the switch blade at a substantially fixed elevation with respect to the contact 16. Thus, as shown in Fig. 4, when the cam roller 67 is at about the lower extremity of cam slot portions 68a, the contact member 33 on the end 65 of the blade has not been lowered to any material degree with respect to the contact 16. Slight lateral and angular movements of the blade are accommodated by the pivotal mounting of contact 16. Before the cam roller 67 has reached 70 the lower extremity of cam slot portions 68a, cam roller 52 passes the lower extremity of cam 81, thus causing the pressure contact 39 to be retracted under the urge of springs 42 and 47. Further rotation of crank 59 causes cam roller 75

67 to progress along the cam slot portions 68b, with the result that such movement is accompanied by downward swinging movement of the blade. For the major part of the movement 5 along the cam slot portions 68b, the springs of counterbalancing units 71 are being compressed, to properly counterbalance the moving parts of the switch.

In closing the switch, a reverse torque is applied to insulator 12, and crank 59 is rotated in a clockwise direction as shown in Fig. 1. By the time cam roller 67 has reached the lower extremities of cam slot portions 68a, the free end of the blade has been swung to the position illustrated in Fig. 4, although the pressure contact 39 is still retracted. Final rotation of the crank 59 in a clockwise direction brings roller 52 into engagement with the surface of cam 81, thus causing the pressure contact 39 to be urged into tight engagement with the contact 16.

It is evident that from the instant pressure contact 39 has been properly urged against the contact 16, crank 59 may overthrow to a considerable degree, without detrimental results. Likewise, when the switch blade is in the position shown in Fig. 1, lever 19 is in dead center position with respect to link 66, so that further turning movement of lever 19 causes a lowering of cam roller 67 in slot portions 68a. Thus, a tolerance is afforded on both sides of the dead center position of crank 19, within which contact 39 remains pressed against contact 16. To cite a particular example, the motor is arranged to normally arrest closing movement of lever 19 when this lever is in dead center position with link 66. As lever 19 approaches such dead center position, contact 39 is first pressed upon contact 16, during initial upward movement of roller 67 in slot portion 68a. Thereafter, lever 19 may continue say 13½ degrees to dead center position and 13½ degrees past dead center position, while the switch remains closed. Therefore lever 19 may stop anywhere within a total tolerance of 27 degrees, and if such tolerance is accidentally exceeded, no harm will result, except that the switch will be opened.

A further characteristic of my switch is that if certain parts become broken, as for example the arm 64 of crank 59, the link 66, or the crank 19, the switch will remain closed and will not immediately drop to open position. This is because, when the switch is closed, the stationary contact 16 is being tightly gripped by the pressure contact 39, and also because of the angularity of cam slot portions 68a with respect to the application of counterbalancing forces from the counterbalancing units 71. Likewise, in the event the counterbalancing units become disrupted, the switch will not drop open, because of the friction occasioned by the lateral thrust of cam roller 67 upon the sides of cam slot portions 68a. The cam slots 68 not only modify movement applied to the blade 14 to secure the results described, but also serve to control the application of counterbalancing forces so that the parts are properly counterbalanced during both opening and closing of the switch. Thus, there will be no undue speeding-up of the operating motor when the switch is being opened.

In the particular modification described herein, the switch has been mounted for downward swinging movement of the blade to open position. However, it is evident that the switch can be variously positioned, depending upon the con-

ditions or problems encountered in a particular installation.

I claim:

1. In an electrical switch, a movable blade, a relatively stationary contact adapted to co-operate with one end of the blade, a crank having spaced pivotal connections with the other end of the blade and with a fixed support respectively, a stationary cam, a lever arm fixed to the blade and effectively engaging said cam, said cam having one portion thereof adapted to afford a substantial amount of continued movement of the crank after the blade has been moved to substantially closed position with respect to the stationary contact, and having another portion thereof formed to afford swinging movement of the blade between open and closed positions, and counterbalancing means connected to said lever arm, whereby said cam serves to simultaneously vary the effective counter-balancing of the blade.

2. In an electrical switch, a movable blade, a contact member secured to one end of the blade, a relatively stationary contact adapted to co-operate with the contact member of the blade, means including an operating member serving to carry and permit swinging movement of the blade between open and substantially final closed positions, said last means affording a substantial increment of continued movement of the operating member after the blade has been moved to substantially final closed position, an additional pressure contact movably carried by the blade and adapted to engage said stationary contact, and means including a cam, operating within the limits of said continued movement, for urging the pressure contact into forceful engagement with the stationary contact whereby the stationary contact is tightly clamped between the pressure contact and the first-named contact member of the blade.

3. In an electrical switch, a blade having a contact member secured to one of its ends, a relatively stationary contact adapted to co-operate with the contact member of the blade, with the blade contact member engaging one side face of the relatively stationary contact, means including an operating member serving to carry and permit swinging movement of the blade between open and substantially final closed positions, said last means affording a substantial increment of continued movement of the operating member after the blade has been moved to substantially final closed position, an additional pressure contact movably carried by the blade and adapted to engage the opposite side face of said relatively stationary contact, and means including a cam, operating within the limits of said continued movement, for urging the pressure contact into forceful engagement with the stationary contact whereby the stationary contact is tightly clamped between the pressure contact and the first-named contact member of the blade.

4. In an electrical switch, a blade having a contact member secured to one of its ends, a relatively stationary contact adapted to co-operate with the contact member of the blade, with the blade contact member engaging one side face of the relatively stationary contact, means including an operating member serving to carry and permit swinging movement of the blade between open and substantially final closed positions, said last means also including a cam serv-

ing to modify motion of the blade and affording a substantial increment of continued movement of the operating member after said one end of the blade has been moved to substantially final closed position, an additional pressure contact movably carried by the blade and adapted to engage the opposite side face of said relatively stationary contact, and means including a sec-
ond cam, operating within the limits of said continued movement, for urging the pressure contact into forceful engagement with the stationary contact whereby the stationary contact is tightly clamped between the pressure contact and the first-named contact member of the blade.

JOS. S. THOMPSON.
